(57) **CLAIM**

The ornamental design for a hydraulic actuated plow system, as shown and described.

DESCRIPTION

FIG. 1 is a front perspective view of a hydraulic actuated plow system showing my new design;

FIG. 2 is a front view thereof;

FIG. 3 is a right side thereof;

FIG. 4 is a left side view thereof;

FIG. 5 is a top plan view thereof;

FIG. 6 is a bottom plan view thereof;

FIG. 7 is a front perspective view of a second embodiment of a hydraulic actuated plow system showing my new design;

FIG. 8 is a front view thereof;

FIG. 9 is a right side view thereof;

FIG. 10 is a left side view thereof;

FIG. 11 is a top plan view thereof; and,

FIG. 12 is a bottom plan view thereof.

Any broken lines shown in the drawings are for illustrative purposes only and form no part of the claimed design.
